Patented Dec. 31, 1912.

UNITED STATES PATENT OFFICE.

JOSEPH BERNARD AND WILLIAM S. CLAYTON, OF VANCOUVER, B.C., BRITISH COLUMBIA,
CANADA.

SEAM-PRESSING MACHINE.

1,048,794

Specification of Letters Patent. Patented Dec. 31, 1912.

Application filed August 23, 1912. Serial No. 716,604.

To all whom it may concern:

Be it known that we, JOSEPH BERNARD and WILLIAM S. CLAYTON, a subject of the Emperor of Germany and a citizen of the Dominion of Canada, respectively, residing at Vancouver, in the Province of British Columbia, Canada, have invented a new and useful Seam-Pressing Machine, of which the following is a specification.

10 This invention relates to a seam pressing device which has been designed to fold over and press down the edges of the seams in clothing and the like. This work is commonly performed by hand with a heavy pressing iron but is not an operation that calls for any particular manipulative skill, and with proper provision can be more rapidly and satisfactorily done by a machine. Although separate as a mechanism, the machine may, if so desired, be connected to and be operative with the sewing machine by which the seam is run.

The invention comprises a means for conveying the material under the pressing iron 25 and in combination with the pressing iron a down folding and guiding attachment that will direct the seam evenly under the iron. The supporting means must be such as will allow closed seams, like the arms of coats 30 and the legs of trousers to pass.

The invention is particularly described in the following specification, reference being made to the drawings by which it is accompanied, in which:

35 Figure 1 is a side elevation of the machine. Fig. 2, an end elevation. Figs. 3, 4, 5 and 6 are enlarged details in side elevation, plan, end elevation and cross section of the seam opening and down-folding device. Fig. 7 40 is a detail elevation of a modification of the invention.

In these drawings 2 represents an endless conveyor band of strong, flexible fabric, which band passes over driving and end 45 pulleys 3 and 4 mounted at the base and extreme other end respectively of a suitable overhanging frame 5. This frame 5 is shown in the drawing as extending upward from the floor level to a convenient height 50 for the operator and bending with an easy curve to the horizontal, but may, where the circumstances are favorable, be bracketed from a wall or extend along a bench. This frame 5 may be made up of two side plates 55 maintained the required distance apart by

shouldered spindles 7, on which run carrying rollers 8 to support the band above the depth of the frame on the upper side and within its depth on the under or return side. This is desirable as enabling a garment having a closed seam to pass freely along the supporting frame. Adjacent to the place of application of the pressing iron 10 the carrying rollers 8 give place to a block of wood 9 secured between the side plates of the frame, 60 which block sustains the band 2 under the pressure of the iron.

The pressing iron 10 is of the usual form and weight and may be heated in any approved manner, either by electric current or 70 by gas or gasoline flame. It is mounted loosely on a handle lever 12 which is pivoted at 13 so that the iron may be lifted clear by means of the handle which projects beyond the iron to the front of the machine. In the 75 drawing the lever 12 is shown as carried on an independent column 14 from the floor level and the pivot joint of the lever has a stop 11 that will sustain the lever, when out of use, in a convenient position for the 80 operator.

Secured to the front end of the iron 10 and projecting forward from it in continuation of its middle line is a presser bar 15. This is a thin, flat bar having a downwardly 85 projecting mid-rib or seam guide 16, see Fig. 6. At its extreme end this member 15 is upwardly turned and narrowed to a blunt point, the longitudinal guiding rib 16 projecting beyond the end, as at 17. This upwardly turned end and projecting fin 17 are designed to divide the seam and fold the edges down, one on each side under the presser bar 15.

To guide the seam vertically to the dividing fin 17, a member 20 is secured to the presser bar 15 just within the upwardly turned end, and extends for a short distance beyond it, said member being apertured, as at 21, to enable the upwardly turned end of 100 the seam presser guide to pass through it and is divided medially from the aperture, providing an open slit 22 through which the united edges of the seam may pass that they may be presented to the dividing fin 105 17 in proper alignment to be divided by that fin. The edges and end of this slit 22 are flanged upward, as at 23, see Figs. 3, 4 and 5.

In use a garment, after having had its seams sewn, is placed upon the free over- 110

hanging end of the frame 5 and the upstanding edges of the seam are together inserted into the slit 22 of the member 20. The conveyer band 2 draws the work under the 5 presser bar 15 and the dividing fin 17 and upwardly turned end of bar 15 open the edges of the seam and fold them over, one on each side. As the cloth passes under the presser bar 15 its mid-rib 16 rectifies the 10 seam so that it will pass fairly and evenly under the pressing iron 10.

Means may be furnished as shown in Fig. 7, by which the edges of the seam may be damped with water as it passes to the 15 pressing iron. By reference to Fig. 7 it will be noted that a suitable water reservoir 20^a may be provided to deliver water through its spout 20^b and hole 20^c to the seam.

If the garment is an open one, it may pass 20 direct onto a table adjacent after each seam has been pressed but, if closed, the frame 5 is of sufficient length from its support to provide accommodation for a number of them to collect against a shelf 25 before it is 25 necessary to stop the machine to remove them.

The machine may be made for light material, such as silk, or for the heaviest character of cloth seamed in this manner and the 30 iron with its attached presser bar, etc., should be easily removable for the substitution of one of different weight, when required.

Having now particularly described our 35 invention, we hereby declare that what we claim as new and desire to be protected in by Letters Patent, is:

1. A seam pressing machine, comprising in combination, a presser block, a pressing 40 iron sustained in position over the block, a seam opening, folding and guiding device, secured to the front end of the iron and extending forward from it, and means for passing the cloth with the seam to be pressed 45 under the pressing iron.

2. A seam pressing machine, comprising

in combination, an endless band traveling over a presser block, a pressing iron sustained in position over the block and having seam opening, down-folding and guiding devices connected to its front end. 50

3. A seam pressing machine, comprising in combination, an endless band traveling over a presser block, a pressing iron sustained in position over the block and having seam opening, folding and guiding devices 55 connected to its front end, and means for mechanically lifting the pressing iron and its attachments off the presser block.

4. A seam pressing machine, comprising in combination, a presser block, a supporting frame in which such presser block is carried, an endless conveyer band passing over the presser block and outside of the supporting frame on the upper side and within 65 the contour of that frame on the underside, a seam pressing iron carried on a lever pivotally mounted at the approximate level of the presser block, said lever having a handle projecting from the iron to the front of the 70 machine.

5. A seam pressing machine, comprising in combination, a presser block, a seam pressing iron sustained in position resting over the block, a presser bar secured to the front 75 end of the iron and extending forward from the iron, said bar having a downwardly projecting mid-rib in alignment with the middle line of the iron and an upwardly turned end with a continuation of the mid-rib projecting forward from it, and means for directing the closed edges of the seam medially to the forwardly projecting end of the mid-rib. 80

In testimony whereof we have signed our 85 names to this specification in the presence of the two subscribing witnesses.

JOSEPH BERNARD.

WILLIAM S. CLAYTON.
